US0D1050822S

(12) **United States Design Patent** (10) Patent No.: **US D1,050,822 S**
(45) Date of Patent: ** Nov. 12, 2024

(54) **BREAD FERMENTATION BASKET**

(71) Applicant: **Guangzhou Wehomate Houseware Co., Ltd.**, Guangzhou (CN)

(72) Inventor: **Xingshao Li**, Beijing (CN)

(73) Assignee: **GUANGZHOU WEHOMATE HOUSEWARE CO., LTD.**, Guangzhou (CN)

(**) Term: **15 Years**

(21) Appl. No.: **29/906,028**

(22) Filed: **Oct. 30, 2023**

(30) **Foreign Application Priority Data**

Oct. 10, 2023 (CN) 202330653834.2

(51) LOC (14) Cl. **07-07**

(57) **CLAIM**

The ornamental design for a bread fermentation basket as shown and described.

DESCRIPTION

FIG. 1 is a first perspective view of a bread fermentation basket showing the new design;

FIG. 2 is a second perspective view thereof;

FIG. 3 is a front view thereof;

FIG. 4 is a rear view thereof;

FIG. 5 is a left side elevational view thereof;

FIG. 6 is a right side elevational view thereof;

FIG. 7 is a top view thereof;

FIG. 8 is a bottom view thereof; and,

FIG. 9 is a cross sectional view along 9-9 of FIG. 3.

1 Claim, 9 Drawing Sheets
